UNITED STATES PATENT OFFICE.

GEORGE MOCK, OF BARDSTOWN, KENTUCKY.

GATE.

1,136,157.

Specification of Letters Patent. Patented Apr. 20, 1915.

Application filed November 19, 1914. Serial No. 873,026.

To all whom it may concern:

Be it known that I, GEORGE MOCK, a citizen of the United States, residing at Bardstown, in the county of Nelson and State of Kentucky, have invented a new and useful Gate, of which the following is a specification.

The device forming the subject matter of this application is a gate and one object of 10 the invention is to provide a novel means for operating the gate, said means comprising two pivotally connected elements adapted to be folded with respect to each other to open the gate, means being provided whereby the 15 said elements may be held in alinement, to the end that the same may act as a rigid brace for holding the gate closed.

Another object of the invention is to provide a novel form of weight for the lever 20 portion of the gate operating mechanism, the weight acting as a stop to maintain the lever and the link which is connected therewith in alinement.

Another object of the invention is to provide novel means for assembling the link 25 with the gate.

With the above and other objects in view which will appear as the description proceeds, the invention resides in the combination 30 and arrangement of parts and in the details of construction hereinafter described and claimed, it being understood that changes in the precise embodiment of the invention herein disclosed can be made within 35 the scope of what is claimed, without departing from the spirit of the invention.

In the accompanying drawing:—Figure 1 shows the invention in perspective; Fig. 2 40 is a side elevation of the mechanism for operating the gate; Fig. 3 is a top plan of the mechanism for operating the gate, a portion of the gate appearing as an added feature.

In the drawings there is shown a fence 1 45 terminated at a supporting post 2 and at a striking post 3. Hingedly mounted as shown at 4 upon the supporting post 2 is a swinging gate 5 which may be of any desired construction.

Connected with the gate 5 intermediate its ends is a pivot element 6 provided at one end with an enlarged head 7 preferably of circular contour.

The invention comprises a link 8 fashioned from a single strip of metal bent into

U-shape, the bend of the link being indicated by the reference character 9. In the bend 9 of the link there is formed a slot 10 through which the pivot element 6 passes, the head 7 of the pivot element 6 lying 60 within the contour of the bend 9. In advance of the head 7, the side arms of the link 8 are contracted as shown at 11. The side arms of the U-shaped link 8 are contracted at their free ends to form fingers 12 65 through which a pivot element 14 passes.

A lever 15 is mounted intermediate its ends to swing upon the pivot element 14. Attached to one end of the lever 15 is a weight 16. The weight 16 at one end is 70 adapted to enter between the side arms of the link 8 and in order to facilitate the entry of this end of the weight between the side arms of the link, the side faces of the weight 16 adjacent one end converge to a 75 point as shown at 17. Inserted through the weight 16 is a cross pin 18. The cross pin 18 is adapted to engage the upper edges of the side arms of the link 8 when the lower end of the weight 16 enters between the side 80 arms of the link, to the end that the link and the lever 15 may stand in approximate alinement and serve as a rigid brace adapted to hold the gate 5 in a closed position. The rear end of the lever 15 is mounted on 85 a shaft 19 supported upon short posts 20 inserted into the ground.

Pivotally connected at 22 with the lever 15 intermediate the shaft 19 and the pivot element 14 is a U-shaped yoke 21 with the 90 upper end of which are connected flexible elements 23 leading to the adjacent ends of primary levers 24 fulcrumed intermediate their ends as shown at 25 upon posts 26. The U-shaped yoke 21 is adapted to receive 95 one end of the weight 16 when the lever 15 is raised. Mounted on the posts 26 are brackets 27. Supported in the brackets 27 and in the posts 26 are pivot elements 28 constituting fulcrums for secondary levers 29 united with the primary levers 24 by means of links 30. Flexible elements 31 depend from the free ends of the secondary levers 29. If desired, the secondary levers 29 may be dispensed with, the primary levers 24 being of a sufficient length to permit a satisfactory operation of the gate.

Owing to the fact that the link 8 is contracted as shown at 11 in front of the head 7 of the pivot element 6, and owing to the 110

fact that the pivot element 6 passes through the slot 10 in the bend 9 of the link 8, an effective and satisfactory pivotal connection between the gate and the link 8 is established and at the same time, the link 8 cannot be thrust toward the gate 5 sufficiently to effect a bending of the pivot element 6. The pivot element 6 passes loosely through the slot 10, sufficient play being afforded so that the link may move not only horizontally but vertically as well.

Owing to the pointed construction of the weight 16 as indicated at 17, the lower end of the weight will be guided between the side arms of the link 8 when the gate is closed. The cross pin 18 coacts with the upper edges of the side arms of the link 8 to hold the link and the lever 15 in alinement and thus as clearly shown in Fig. 1 of the drawings, the gate is held braced in a closed position. The link and the lever constitute not only a means for opening and closing the gate, but, as well form in effect, a latch mechanism for holding the gate closed.

The general operation of structures of this type is well understood by those skilled in the art, but it may be stated that when one flexible element 31 is pulled upon, one lever 29 and ultimately the corresponding lever 24 is tilted, the flexible element 23 raising the yoke 21, the latter swinging upon its pivotal connection 22 with the lever 15 and raising the lever, the lever swinging on the shaft 19. The lower end of the weight 16 is withdrawn from between the arms of the link 8 and the inner ends of the link and the lever move upwardly, thus effecting an opening of the gate, the lever 15 swinging rearwardly past the vertical. When the flexible element 31 is drawn upon, the other lever and the weight 16, will swing forwardly and resume the positions shown in Fig. 1 of the drawing.

Copies of this patent may be obtained for five cents each, by addressing the "Commissioner of Patents, Washington, D. C."

Having thus described the invention, what is claimed is:—

1. In a device of the class described, a swinging gate; a link pivoted to the gate and comprising spaced parts defining an opening; a lever pivoted intermediate its ends between the parts of the link; a transverse weight on one end of the lever and provided with a tapered end adapted to enter the opening thereby to guide the lever between the parts of the link, the weight comprising a lateral projection coöperating with the link to hold the link and the lever in approximate alinement whereby the link and the lever will act as a brace to hold the gate closed; means for pivotally mounting the other end of the lever; and means for raising the lever.

2. In a device of the class described, a swinging gate; a U-shaped link; a pivot element connecting the bend of the link with the gate; a pivot element connecting the ends of the arms of the link; a lever mounted to swing intermediate its ends upon the last named pivot element; a transverse weight on one end of the lever and including a guiding end adapted to enter the link; a projection on the weight and adapted to engage the upper edges of the arms of the link thereby to hold the lever and link in approximate alinement, whereby the lever will act as a brace to hold the gate closed; means for pivotally supporting the other end of the lever; a U-shaped yoke pivoted to the lever and adapted to receive the other end of the weight when the lever is raised.

In testimony that I claim the foregoing as my own, I have hereto affixed my signature in the presence of two witnesses.

GEORGE MOCK.
